Germany, a corporation of Germany

Application June 14, 1952, Serial No. 293,705

6 Claims. (Cl. 340—345)

In connection with statistics and for coding purposes, non-systematic, random sequences of figures and letters are required to a constantly increasing extent.

These sequences have hitherto been produced in a very complicated and time-wasting manner, usually by hand, it only seldom being possible to obtain a really good random sequence, especially when they are derived manually.

A process has consequently been developed which produces random sequences of figures and letters in a fully automatic manner, and which in the technical assembly is so simple and operates in such an easily supervised manner that in practice the random sequence derived is assured even in continuous service.

One embodiment of the invention is more fully described by way of example in the following.

The complete assembly can be regarded as comprising two sections. Section 1 represents an arrangement for generating non-systematic short electrical impulses, namely, the impulse transmitter. Section 2, which is a valve trigger arrangement with two stable end positions, is operated by these impulses.

The following detailed operation is produced by the constructional example: Upon operating the key T_a , the control voltage U_{st} charges the condenser C_{L1} and, through R_L , also the condenser C_{L2} . When the voltage at C_{L2} reaches the igniting voltage of the relaxation oscillator valve I, C_{L2} is discharged. The valve I continuously generates additional sweep voltage impulses as long as the key T_a is closed and as long as energy can still continue to flow from the condenser C_{L1} to C_{L2} after the key is opened.

If the key T_a is operated for a predetermined time, the number of sweep voltage impulses generated by the valve I depends on a large number of other determining values as well as on the time t , namely: upon the control voltage U_{st} , upon C_{L1} , R_A , R_L , C_{L2} , C_K , R_K and above all upon all the momentary electrical working conditions of the relaxation Kipp oscillator valve I. As a consequence of this large number of non-systematic variables, when T_a is repeatedly actuated, the number of the relaxation oscillation impulses generated is subjected to non-systematic fluctuations even when the time t is constant. In addition, when operating the arrangement in practice, the time t also undergoes small fluctuations when the key T_a is actuated rhythmically, so that in this way a further non-systematic variable is provided.

If the control voltage U_{st} is taken from the mains without stabilisation, the normal mains voltage fluctuation is obtained as a non-systematic variable. An even greater uncontrolled fluctuation is obtained if the output level of a noise generator (valve noise) or the noise of radioactive counting tube amplifiers are also used for the control.

It has been shown by experiments that the large technical expense this would involve is not necessary, since it does not provide any improvement in the random sequence

for the complete arrangement. The non-systematic fluctuations of the other determining valves of the impulse transmitter are definitely sufficient.

The valve II, which serves to amplify the voltage impulses, is acted upon by the relaxation oscillation valve I through the coupling condenser C_K and the coupling resistance R_K .

The impulsing of the trigger arrangement, which operates with the valves III and IV, is effected by the anode of the valve II. In accordance with the circuit arrangement, one of the said valves III and IV is always blocked by the negative grid biasing while the other is open. If an impulse occurs symmetrically on both grids, the blocked valve is opened thereby and the valve which was previously open is closed.

Consequently, if an even number of impulses is sent to the trigger arrangement upon actuating the key T_a , the trigger arrangement is in the initial position again after the impulses have finished. On the contrary, an odd number of impulses causes a new end position.

In conjunction with the impulsing by the impulse transmitter, the trigger arrangement operates in the manner of an electrical dice, which swings rapidly backwards and forwards between its two end positions and finally, according to the number of impulses acting thereon, remains stationary on even or odd.

According to the position of the trigger arrangement, the indicator relay R disposed in the anode circuit of the valves III and IV positions its contact on positive or negative.

If the key T_a is operated systematically by any technical control arrangement, there is obtained a non-systematic random sequence of positive and negative values, resulting from the non-systematic dispersions of the impulse transmitter.

It is only a duty of the normal switching technique to operate simultaneously 5 or 6 or any desired number of electrical cubes by the key T_a in order in this manner to establish, with one actuation of the key, for example, a complete five-unit or six-unit signal of the teleprinter art, that is to say, a number or a letter.

Accordingly, a complete five-unit or six-unit signal is also defined by 5 or 6 processes with one dice.

Since the electric valve circuits have only a very low inertia, the operating speed is substantially only limited by the inertia of the indicating relay R, where the result is not indicated by inertia-free indicator elements such as glow-discharge lamps and the like.

During tests, it was possible to carry out up to 500 operations per second. This corresponds in the five-unit code to an output of 100 letters or figures per second.

As regards the technical execution and the method of operation of the electrical dice, it is immaterial whether ion tube trigger arrangements or suitable electron tube circuits are employed for generating the electrical impulses. Similarly, it does not affect the method of operation if the trigger device in the electrical dice is built up of two mutually blocking electron tubes or only of one or more ion tubes.

The sequences of figures and letters derived with the electrical dice may be used in many ways as number tables for statistical investigations, as groups of figures or letters for the purpose of hand ciphering or they may be stamped in perforated tapes as five-unit signals for automatic ciphering and the like.

I claim:

1. A random digit selecting system, comprising a source of control voltage, a normally blocked generator, means associated with said source of control voltage to shock-excite said generator and cause it to deliver a short train of pulses per shock, whereby the number of said pulses

is odd or even at random depending on momentarily prevailing oscillating conditions of said generator, a counter circuit which is adapted to be controlled depending as to whether the number of pulses of the pulse trains applied is odd or even, and means applying said trains of pulses to said counter circuit.

2. A random digit selecting system, comprising a direct current source of control voltage, a normally blocked generator, means keying said direct current voltage to shock-excite said generator and cause it to deliver a short train of pulses per shock, whereby the number of said pulses is odd or even at random depending on the momentarily prevailing oscillating conditions, a counter circuit which is adapted to be controlled depending as to whether the number of pulses of the pulse trains applied is odd or even, and means applying said trains of pulses to said counter circuit.

3. A random digit selecting system, comprising a random noise source, a normally blocked generator, means applying the output of said noise source to shock-excite said generator and cause it to deliver a short train of pulses per shock, whereby the number of said pulses is odd or even at random depending on the momentarily prevailing oscillating conditions, a counter circuit which is adapted to be controlled depending as to whether the number of pulses of the pulse trains applied is odd or even, and means applying said trains of pulses to said counter circuit.

4. A random digit selecting system, comprising a source of control voltage, a normally blocked generator, means associated with said source of control voltage to shock-excite said generator, and storage means between said source of control voltage and said generator, said storage means comprising a first branch condenser, a resistance shunting said first branch condenser, a series resistance and a second branch condenser, the charging capacity of said first condenser being sufficiently high to excite said generator further for a short time interval after the actual shock from said source of control voltage.

5. A random digit selecting system, comprising a source of control voltage, a normally blocked relaxation generator, means associated with said source of control voltage to shock-excite said generator and cause it to deliver a short train of pulses per shock, whereby the number of said pulses is odd or even at random depending on the momentarily prevailing oscillating conditions of said generator, a counter circuit adapted to be controlled depending as to whether the number of pulses of the pulse trains applied is odd or even, and means applying said trains of impulses to said counter circuit.

6. A random digit selecting system, comprising a source of control voltage, a generator of the gas-discharge type, storage means between said source of control voltage and said generator, means associated with said source of control voltage to shock-excite said generator and cause it to deliver a short train of pulses per shock, whereby the number of said pulses is odd or even at random depending on the momentarily prevailing oscillating conditions of said generator, an amplifier stage, a counter circuit consisting of a two-condition-circuit adapted to be triggered by the pulses of the pulse trains supplied from said amplifier stage and to rest in either of its two stable conditions after a respective pulse train is finished corresponding to its even or odd number of pulses, means applying said trains of pulses via said amplifier stage to the input of said counter circuit, and a relay connected to the output of said two-condition-circuit and responding to said two condition.
